UNITED STATES PATENT OFFICE.

ROY O. WILLIAMS AND HARRY B. COEN, OF COLUMBUS, OHIO.

WATER-COOLING DEVICE.

1,092,316.

Specification of Letters Patent. Patented Apr. 7, 1914.

Application filed August 2, 1912. Serial No. 712,886.

To all whom it may concern:

Be it known that we, ROY O. WILLIAMS and HARRY B. COEN, citizens of the United States, residing at Columbus, in the county 5 of Franklin and State of Ohio, have invented certain new and useful Improvements in Water-Cooling Devices, of which the following is a specification.

Our invention relates to water cooling devices and resides primarily in the provision 10 of a water cooling device which combines the action of a pump with the action of cooling the water and thereby renders possible the elimination of all pumping means or other 15 devices for forcing the water to the cooling device under normal conditions.

Our invention is primarily applicable to 20 the cooling of the jacket water of internal combustion engines and particularly of engines upon automobiles, although the scope 25 of our invention is not limited to this particular art.

The primary essential of our improvement resides in the fact that the water to be 30 cooled is drawn in positively by the action of the cooling device. This cooling device preferably takes the form of a rotating element which acts by its rotation to suck in the water and to discharge it in the path of 35 air. This rotating element is preferably formed to simultaneously draw in a certain quantity of air for mixing and direct contact with the indrawn water. Also, the indrawn water is preferably discharged into 40 contact with the indrawn air in disintegrated form and is preferably caused to be broken up into flying globules presenting a gradually increased superficial area to be 45 acted upon by the cooling air. By the utilization of our improvement, we are enabled to do away with the usual pump attached to water cooling devices for maintaining circulation and in the application of our device to motor vehicles, we are enabled to dispense 50 with not only this pump, but the fan which is utilized in the present day type of cooling apparatus for automobiles. Our improvement in application to the normal automobile, produces a saving of approximately 55 ninety per cent. of the cost of construction, for the reason that it takes the place of the radiator, the pumping device and the fan.

The preferred embodiment of our invention is shown in the accompanying drawings, 55 in which similar characters of reference designate corresponding parts, and in which:

Figure 1 is a side elevation of an automobile engine with our cooling device applied thereto and shown as positively driven from the driving shaft of the automobile, 60 Fig. 2 is a side elevation of our improved cooling device detached, Fig. 3 is an end view of the structure shown in Fig. 2, Fig. 4 is a section taken on line 4—4 of Fig. 3, and, Fig. 5 is a section taken on line 5—5 of Fig. 4. 65

Inasmuch as the cooling device proper is the essential element of our invention, it will be well to describe this cooling device initially, therefore attention is directed to Figs. 2, 3, 4 and 5 wherein there is shown a casing 1 preferably of drum-like form having a water outlet 2 at a lower point in one side thereof which is in turn provided with an outwardly leading air passage 3. This drum-like casing may be formed with a cylindrical 70 body 4 and annular side pieces 5 and 6 having their centers cut away as at 7 and formed with inwardly bent edges 8 and 9 forming annular troughs to catch and conduct the dripping water from the inner surfaces of 75 the side pieces so as to preclude the downward drip of the water from the side walls across the central cut-out portion. The cylindrical body portion 4 desirably incloses a plurality of cylindrical screens 10 and 11 which are 80 preferably spaced apart by spacing elements 12 and which in turn surrounds a somewhat smaller rotary element comprised of spaced rings 13 and 14 held apart by and carrying 85 fan blades 15 preferably concaved in the 90 direction of travel of the said rotary element and preferably arranged at determinate intervals. These ring members 13 and 14 are further provided with inwardly projecting 95 lips 16, whereby they are mounted upon the 100 transverse conduit elements 17 of hollow radial spokes 18 connected by a sleeve 19 with a hollow shaft 20 which preferably has one 105 end closed as at 21 and its other end open as at 22 for connection to and feeding by a 110 source of water supply which is not shown in the said Figs. 2, 3, 4 and 5, but which may be similar in form to that shown in Fig. 1. This hollow shaft 20 is mounted in bearing sleeves 23 and 24 carried by bearing brackets 105 25 and 26 and the said shaft is held against lateral movement in these bearing sleeves by means of collars 27 and 28 which may be locked upon the said shaft by set screws 29. The shaft is rotated by any suitable means 110 and we have shown a bevel gear 30 as a medium of rotation.

In operation of this device, the rotation of the shaft 20 while in communication with a column of water, will operate by a centrifugal and siphoning action of the rotating hollow spokes to continually draw in water and discharge it through apertures 31 in the transverse conduit elements mounted upon the ends of the spokes. Simultaneously the fan blades 15 will serve to draw 10 in air through the cut-out central portions of the side pieces 5 and 6 and will cause a constant current of air passing through the casing. The water will be discharged from the transverse conduit elements by the combination of a suction produced by the travel 15 of the said transverse pieces through the air, a siphoning action and centrifugal force. In its discharge from these transverse conduit elements, the water is partially disintegrated and flies through the air until it reaches either the fan blades 15 or the reticulate elements 10 and 11. The major portion of the discharged water will strike upon the fan blades 15 and will be broken up into 20 flying globules of water in direct contact with the indrawn air at the strongest point of its draft. There will necessarily result a rapid and efficient cooling action, due largely to the fact that the water is broken up and 25 evenly distributed around the path of draft and is permitted to pass through the atmosphere and in direct contact therewith from the moment it leaves the transverse conduit elements until it is delivered from the spout 2 of the casing. It will be understood that the air likewise passes through the spout 2 until it reaches the supplemental spout 3, when it will naturally rise and pass therethrough. The general course of 30 the water and the direction of travel of the rotary element has been denoted by arrows upon the drawings.

In the structure shown in Fig. 1, our cooling device 1 is shown in application to the 45 engine of a motor vehicle, which motor vehicle comprises a water jacket 32 having circulating pipes 33 leading therefrom and connected as at 34 by a water tight bearing to the open end of the hollow shaft 20. The 50 delivery spout 2 of the casing is further shown as connected by piping 35 with a tank 36 from which leads a manifold pipe element 37 into the jacket 32. This manifold pipe element has its lower end extending directly into the tank 36 and may be joined therewith by a threaded sleeve 38 and a union 39. At this point of union, we desirably mount a check valve 40 under the control of a spring 41. The purpose of this 55 check valve is to maintain a head of water in the jackets and circulating pipes of the engine. The hollow shaft 20 with its bevel gear 30 is preferably driven by a coacting bevel pinion 42, shaft 43, bevel pinion 44 60 and bevel gear 45 mounted upon the driving

shaft 46 of the engine, this driving shaft being of normal form and being shown in connection with a cranking means 47 which may be of any suitable form.

In the operation of this apparatus the 70 water is drawn from the water jacket surrounding the cylinders, through pipes 33 and into the hollow shaft, and is discharged radially through the spokes of the rotating element into the casing, where it is cooled 75 and passes from thence through delivery spout 2 to the tank 36, from which water is supplied to the water jackets of the cylinders through pipe 37. The continual suction maintained by the rotating element, 80 causes the water to continue its circulation through the pipes 37, water jackets, pipes 33, casing 1, and tank 36, while the check valve in pipe 37 prevents the back flow from the water jackets to the tank and also supports a sufficient volume of water, in said 85 pipe when the apparatus is at rest, to start up the circulation simultaneously with the commencement of rotation of the hollow shaft 20.

90 What we claim, is:

1. In a water cooling device, the combination of a casing, a positively driven rotating water discharging means within the casing and through which water is discharged into the 95 casing and suction devices located intermediate the discharge end of said water discharging means and the wall of the casing for drawing air into the casing whereby when the water is discharged from said discharging means, it comes in contact with the moving volume of air within the casing. 100

2. In a water cooling device, the combination of a casing, a positively driven rotating hollow shaft within the casing, water spraying device carried by said hollow shaft and through which the water is discharged from 105 said shaft, and suction devices intermediate the outer ends of the spraying device and the wall of the casing and moving with said 110 spraying devices for drawing air into the casing whereby when the water is discharged from said spraying device it comes in contact with the moving volume of air in the casing. 115

3. In a water cooling device, the combination of a casing, rotating means for discharging water into the latter, and positively driven air suction means located between the wall of the casing and the discharge end of the water discharging means and in the path of the water discharged from the latter, whereby the water discharged from the water discharging means will pass through the air drawn into the casing and be broken into globules by its contact with the suction means. 120

4. In a water cooling device, the combination of a reservoir, a casing, a rotating element located within the casing and provided 125

with water spraying devices, rotating means within the casing for drawing air into the casing, a pipe leading from the casing to the reservoir through which the water passes to the latter, a pipe leading from the reservoir to the mechanism to be cooled and a pipe leading from the latter to the rotating element in the casing, the parts being so constructed that circulation through the casing, reservoir, pipes and mechanism to be cooled is maintained by suction and the centrifugal action of the rotating element.

5. In a water cooling device, the combination of a casing, a positively rotated water inlet pipe, a hollow radial spoke carried by and communicating with said pipe for discharging the water into the casing and means carried by the rotating pipe and located intermediate the discharge end of the 15 hollow radial spoke and the wall of the casing for creating a suction and for breaking up the ejected stream of water into globules.

6. The combination of a casing having a water outlet, a fixed screen in said casing adjacent the outer wall of the latter, a water supply pipe, a rotary element located within the casing and connected with said water supply pipe for projecting water onto the screen, and means rotating in the space between the screen and the water outlet for drawing air into the casing and for breaking up the streams of water into globules.

7. The combination of a casing, a rotating pipe having a series of radial spokes, said spokes having discharge openings in their ends, a pair of spaced rings located at opposite sides of the radial spokes and rotating

therewith, and blades carried by said rings, the said blades being beyond the discharge ends of the radial spokes.

8. The combination of a casing, a screen therein adjacent the outer wall of the casing, a positively rotated water pipe concentric with said screen, radial spokes carried by said pipe through which the water is discharged, and a series of connected blades movable in a path intermediate the free ends of the spokes and the screen.

9. A device for cooling water, comprising a drum like casing having a water discharge pipe, means for discharging water into said casing, a rotating suction device intermediate the casing and said water discharge pipe, and a reticulate surface between the suction device and the casing.

10. A water cooling device comprising a drum like casing, a rotating water discharging device within said casing, suction devices for drawing air into said casing carried by said water discharging device and moving within a path outside of the path of movement of the water discharging device so as to make contact with the discharged water, and a reticulate surface between the suction device and the wall of the casing against which the water is discharged in contact with the indrawn air.

In testimony whereof we affix our signatures in presence of two witnesses.

ROY O. WILLIAMS.
HARRY B. COEN.
